UNITED STATES PATENT OFFICE.

JOSEPH BOREL, OF JEANERETTE, LOUISIANA.

PROJECTILE.

1,313,875.

Specification of Letters Patent. Patented Aug. 26, 1919.

Application filed July 12, 1918. Serial No. 244,633.

To all whom it may concern:

Be it known that I, JOSEPH BOREL, a citizen of the United States, residing at Jeanerette, in the parish of Iberia and State of Louisiana, have invented certain new and useful Improvements in Projectiles, of which the following is a specification.

This invention relates to projectiles, and more particularly to aerial torpedoes.

0 The object of the invention is to provide a projectile in the form of a torpedo carrying a number of bombs which, when the projectile contacts with its target, will be discharged in all directions and each bomb exploded separately after being discharged.

Another object is to provide simple and efficient means to facilitate handling of the projectile without danger.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

10 In the accompanying drawings:—

Figure 1 represents a side elevation of a torpedo constructed in accordance with this invention,

Fig. 2 is a longitudinal central section thereof with the rudder broken off for convenience in illustration,

Fig. 3 is a detail perspective view of one of the bombs detached,

Fig. 4 is a transverse section taken on the line 4—4 of Fig. 1,

Fig. 5 is a similar view taken on the line 5—5 of Fig. 2, and

Fig. 6 is a detail perspective of one of the hammers shown mounted on the portion of the firing pin.

15 In the embodiment illustrated the projectile constituting this invention comprises a main body 1 of cylindrical form having a nose 2 which tapers toward the forward extremity of the torpedo giving a true projectile shape to the completed article.

The main body 1 is centrally and longitudinally bowed to form a chamber 3 and at its butt end has an explosive containing chamber 4 which is closed by a solid cap 5 threaded into the casing of the body por-

tion. A shank or stem 5' extends rearwardly through the cap 5 and is provided at its free end with a rudder 5" which operates as a guide for the projectile in its flight. 60

A tubular nipple 6 extends from the inner face of cap 5 into the chamber 4 and has a spring 7 coiled therearound abutting at one end against the inner face of the cap 5 and at its other end against a washer 8 carried 65 by the firing pin 9 which extends longitudinally through the chamber 3 and out through the nose 2. This firing pin 9 is provided on its front end with a head 10 which is designed to contact with a target or any 70 object which is disposed in the path of the torpedo when projected. On contacting with the target this pin will be forced inwardly against the tension of the spring 7 for a purpose presently to be described. A 75 flange 11 is carried by the pin 9 at a point spaced inwardly from its head 10 and is here shown truncated cone-shaped to conform to the front end of the chamber 12 formed in said nose as is shown clearly in 80 Fig. 2. The front end of the pin is made angular as shown at 13 to prevent rotation of the pin and said angular portion has an aperture 14 extending transversely therethrough which registers with a similar aperture or bore 15 extending transversely through the nose 2 at its extremity, said registering apertures being designed to receive a pin 16 which holds the firing pin in projected position to prevent all possibility 90 of its operating to explode its contents so that it may be safely handled.

Mounted on the firing pin 9 within the body 1 and nose 2 are a plurality of hammers 17 made in the form of spiders each 95 having a hub 18 adjustably mounted on the pin by means of a set screw 19. Radiating from each hub 18 are a plurality of fingers or arms 20, any desired number of which may be employed, according to the number 100 of bombs to be arranged in each series.

The body portion of the torpedo is equipped with a plurality of radially opening pockets 21 in which are designed to be frictionally held bombs 23, explosive carrying chambers 22 being formed at the rear of the bombs in said pockets so that when the explosives contained in said chambers is ignited the bombs will be discharged from the torpedo and simultaneously fuses 24 carried 110 by said bombs will be ignited. These fuses 24 extend at one end into the bomb and at

the other end into the chamber 22 and are in the form of the ordinary time fuse which will ignite the bomb in five seconds, more or less, after it is discharged.

5 Each of the explosive containing chambers 22 has an ignition cap 25 projecting from one end thereof in the path of one of the arms 20 of the hammers carried by the firing pin so that when the head 10 of the 10 firing pin contacts with the object this pin will be forced inward against the tension of the spring 7 causing the arms 20 to forcibly engage the caps 25 and thereby ignite the explosive contained in the chambers 22.

15 Four series of these bombs are here shown and each series contains four bombs as is shown clearly in Fig. 5, thus making sixteen in all carried by the torpedo. When this 20 torpedo is projected and the bombs discharged therefrom in the manner above described, they will radiate in all directions and after leaving the torpedo will explode individually so that a great amount of damage may be accomplished by a single torpedo.

The nose 2 as shown in Fig. 2 is made separate from the body portion 1 and is designed to contain an explosive within the chamber 12 thereof so that said nose will 30 operate as an additional bomb of a larger size than projectiles 23, the explosive therein being ignited by the small caps 25 which ignite the explosives in the chambers 22 at the front end of the body portion 1.

25 The foregoing description and the draw-

ings have reference to what may be considered the preferred or approved form of my invention. It is to be understood that I may make such changes in construction and arrangement and combination of parts, materials, dimensions, etc., as may prove expedient and fall within the scope of the claimed invention.

Having thus fully described my invention, what I claim as new and desire to secure by Letters Patent, is:—

40 A projectile of the class described comprising a cylindrical body portion having a tapered nose at its front end, a closure for the butt end of said projectile, threaded therein, a rudder carried by said closure, a firing pin extending longitudinally through said body portion and projecting at its front end through the nose thereof, a flange on said pin for limiting its outward movement, a 45 coiled spring for forcing said pin outward, a plurality of explosive containing pockets carried by said body portion and opening through the periphery thereof, said pockets being arranged in longitudinally spaced 50 series, firing caps projecting from said pockets, and a plurality of hammers carried by said firing pin and positioned to engage said caps when the pin is moved inwardly.

55 In testimony whereof I hereto affix my signature in presence of two witnesses.

JOSEPH BOREL.
